UNITED STATES PATENT OFFICE.

ELBERT B. EDDY, OF CHICAGO, ILLINOIS, AND WALTER R. CLARK, OF MINNEAPOLIS, MINNESOTA.

HAND-TRUCK.

1,007,677.

Specification of Letters Patent.

Patented Nov. 7, 1911.

Application filed November 2, 1908. Serial No. 460,629.

To all whom it may concern:

Be it known that we, ELBERT B. EDDY, a citizen of the United States, and a resident of Chicago, in the county of Cook and State of Illinois, and WALTER R. CLARK, a citizen of the United States, and a resident of Minneapolis, in the county of Hennepin and State of Minnesota, have invented certain new and useful Improvements in Hand-Trucks, of which the following is a specification.

The invention relates to manually-propelled trucks, such as are generally used at railroad stations and express offices for transporting baggage and packages, between the cars and the station or from one part of the station to another. These trucks when not in use, are usually left on the platform of the station and it frequently occurs that persons hurrying to or from a train, or to the ticket office, stumble over the handle when it is left in lowered position and frequently the railroad or express companies are obliged to pay large claims for damages arising from accidents of this sort. To some extent these accidents may be avoided by providing latches or locks for holding the handle in elevated position. In practice, however, it frequently occurs that baggage-men or expressmen neglect or overlook the necessity of lifting the handle and locking it in raised position particularly when haste is necessary in their work.

A further desideratum in baggage or express trucks is to apply brakes to the wheels of the truck so that it will not be free to be pushed around the platform or off the platform, and onto the tracks where it might cause an accident. It has heretofore been proposed to provide tongue-operated brakes to hold the truck wherever it may be left but in practice it frequently occurs that the expressmen or baggagemen in the hurried performance of their duties, neglect to lift and lock the handle into position to cause the brakes to be applied to the wheel of the truck.

The invention designs to provide an improved truck in which the handle will be

automatically lifted whenever it is released 50 by the operator, so that it will be impossible for any person to stumble over the handle when the truck is not in use, because automatic lifting-means will cause the handle to be held in lifted position at all times, except 55 when the user is holding the handle in lowered position. Therefore it will be impossible for the handle to be in lowered position, except when it is held there by the user and if the latter should hurriedly leave the truck 60 the handle will be automatically lifted into position to avoid a possible accident.

The invention further designs to provide a truck with an automatic brake-operating mechanism which will cause the brakes to be 65 automatically applied when the handle is released by the operator, thus relieving the operator of the necessity of lifting and locking the handle to apply the brakes. Therefore when the brakes are operated by an 70 automatically lifted handle, the latter will at all times, except when held by the user, be in lifted position and the brakes will be automatically applied whenever the user releases the handle and there will be no accidents occurring, either from the handle being 75 left in lowered position or from the truck rolling around or being pushed off the platform.

With these objects in view, the invention 80 consists in the several novel features of construction hereinafter set forth and more particularly defined by claims at the conclusion hereof.

In the drawings: Figure 1 is a side elevation of a truck embodying the invention, the handle being shown in lifted position to which it is automatically shifted and in which it will be held at all times except when in use. Fig. 2 is a similar view, parts 90 being shown in section, the handle being shown in lowered position. Fig. 3 is an inverted plan, the parts being shown in position illustrated in Fig. 1.

The truck comprises a body 10, rear-wheels 11, front-wheels 12, which are mounted at the end of an axle 13, a bolster 13^a secured to said axle, and a turn-table 14

which permits the front wheels and the axle to be swung laterally and all of these parts may be of usual or any suitable construction, as well understood in the art. The handle 15 is connected to the front-axle 13 by pivots 16, so that the handle may be lowered for use and so that the front axle and wheels may be swung laterally to guide the truck.

The handle is normally held in raised position shown in Fig. 1 by a weight 17 which is adjustably connected to a lever 18 by a screw 18'. The lever is pivoted as at 19 in a bracket 20 secured to the bolster 13^a and axle 13 and has its front end pivotally and adjustably connected to the rear end of a link 21. The front end of said link is connected to an arm 22 which is pivoted, as at 23, in the front end of the bracket 20' and is rigidly connected to another but shorter arm 24, said arms 22 and 24 and intermediate part pivoted at 23 forming a double crank having a long and a short arm, whereby movement of said long arm 22 will be imparted to short arm 24 with increased leverage. A rod 25 is connected to the end of arm 24, said arms 22 and 24 and intermediate secured to the handle as at 26. The weight 17 is sufficient to overbalance the pivoted handle 15 and the connection between the lever and the handle is such that it will cause the latter to be held in raised position at all times, except when it is manually held in lowered position for use. The weight and its connection with the handle thus serve as means for automatically lifting the handle when it is released and for retaining it normally elevated above the position in which it is used for drawing the truck. When the handle is in lowered position and released by the operator, weight 17 will cause the rear portion of lever 18 to be lowered to swing said lever about its pivot 19 and to operate the link 21 forwardly to rock arms 22 and 24, which will operate rod 26 to raise the handle 15. Resultantly, whenever the operator leaves the truck the handle will be immediately and automatically raised so that accidents resulting from leaving the handle in lowered position where persons are likely to stumble over it will be avoided. The weighted lever and link-connection for the tongue are arranged in close proximity to the axle to leave as much clearance as possible below the axle and so that when the truck is in use the connections will not encounter obstructions on the platform. Furthermore, the weight-lever 18 is arranged to rise and fall beneath the body of the truck and not in too close proximity to the ground or platform.

A brake-shoe 30 is provided for each of the front wheels 12 being secured to a rod 31 which is pivotally held in a bracket 32 which

is secured to the front bolster 13^a by a bracket 33 and to bracket 20 by a bolt 34 65 which also secures the brackets 20, and 33 together. The brake-shoes are secured to arms 35 at the outer ends of rod 31 so that by oscillation of said rod the brakes will be shifted into or out of engagement with the 70 wheel-rims. The brakes are caused to be automatically applied when the operator releases the handle by a connection between rod 31 and link 21 of the connection for automatically lifting the handle. The connection for automatically operating the brakes comprises an arm 36 rigidly secured or connected to rod 31 and a link 37 pivoted to the lower end of said rod as at 38 and to the link 21 as at 39. The end of link 37 is 80 adapted to be connected to the link 21 by means of either of a series of holes 40 so that the brake-operating connection may be adjusted or set to timely apply the brake-shoes to the wheels. Resultantly, whenever the 85 handle is operated by the automatic lifting-means, link 37 will also operate arm 36 to rock brake-shaft 31 and force the brake-shoes 30 into engagement with the rims of wheels 12, the weight 17 being sufficient to 90 cause the brake-shoes to be held in engagement with the wheel-rims. The invention thus provides an improved truck embodying means for automatically lifting the tongue whenever it is released by the operator and 95 for automatically applying the brakes to the front wheels so that no accident is likely to occur either from permitting the handle to remain in lowered position where some person might stumble over it or the truck 100 might roll or be moved around the platform, because at all times, except when the handle is held by the operator, the handle will be in raised position and the brakes will be set.

The invention is not to be understood as 105 restricted to the details described since these may be modified within the scope of the appended claims without departing from the spirit and scope of the invention.

Having thus described the invention, what 110 we claim as new and desire to secure by Letters Patent, is:

1. The combination in a truck comprising carrying-wheels and a pivoted handle, of means for automatically swinging said handle upwardly above its working range of movement, comprising a counterweighted lever, a link connected to said lever, and connections between said link and handle for increasing the leverage on said handle. 115 120

2. The combination in a truck comprising carrying-wheels and a pivoted handle, of means for automatically swinging said handle upwardly above its working range of movement, comprising a counterweighted lever, a link connected to said lever, a brake 125
